CLAIM

The ornamental design for an instrument panel for vehicle, as shown and described.

DESCRIPTION

FIG. 1 is a front view of an instrument panel for vehicle showing our new design.

FIG. 2 is a rear view thereof.

FIG. 3 is a left view thereof.

FIG. 4 is a right view thereof.

FIG. 5 is a top view thereof.

FIG. 6 is a bottom view thereof.

FIG. 7 is a front, top, left perspective view thereof; and, FIG. 8 is a front, top, right perspective view thereof.

The broken lines depict a boundary around the de-emphasized elements, which illustrate portions of the instrument panel for vehicle which form no part of the claimed design.
